UNITED STATES PATENT OFFICE.

JAMES HOWARD HORNER, OF UPPER WALTHAMSTOW, ENGLAND.

MACHINE FOR SIMULTANEOUSLY PRINTING FIGURES AND WORDS.

Application filed September 18, 1923. Serial No. 663,480.

To all whom it may concern:

Be it known that I, JAMES HOWARD HORNER, a British subject, and a resident of 10 Castleton Road, Upper Walthamstow, 5 in the county of Essex, England, have invented certain new and useful Improvements in Machines for Simultaneously Printing Figures and Words, of which the following is a specification, such as will 10 enable others skilled in the art to which it appertains to make and use the same.

This invention relates to machines for simultaneously printing words and figures and while applicable for various purposes 15 is especially designed for the printing of checks, dividend warrants and the like.

The machine is of that kind in which two rollers each comprising variably rotatable sections are mounted on parallel axes one 20 of said rollers bearing the words to be printed and the other the figures, the said rollers being mounted on the machine and adjacent to a movable platen which carries the check or other paper to be printed; the 25 said platen being movable to press the check on to the rollers when they are set with the requisite words and figures so that they will print, through the medium of an ink band or tape the requisite amounts on the check, 30 the type on the said rollers being usually raised so as to procure the desired impression.

Means may be employed in my machine, as in others, for holding the said printing 35 rollers after setting so as to repeatedly print the same amounts on the check, dividend forms or other paper, it being understood that the platen is moved to and fro as by means of a side lever on the machine.

40 My invention differs from previous constructions chiefly in that I actuate the various sections of the rollers by means of pivoted levers adapted to move over scales bearing different number values, said levers having fixed to them toothed sectors which will turn the sections through suitable toothed gear; the amount of turning being appropriate to the amount the levers are moved so that, for example, if the lever is 45 moved to the figure five on the scale, the sections will respectively turn to present the word "five" and the figure "5" towards the platen and into position to print that amount on the paper carried by the platen.

50 My invention also includes other improve-

ments all of which tend to produce a very efficient and reliable machine.

It will be understood that in a machine adapted to print up to thousands, a separate lever is used for the units, tens, hundreds and thousands, and my machine differs from what has been previously proposed in that the lever for the hundreds can be moved from zero up to 900 and further movement will set it for printing from 1000 to 9000 so that it is possible with the "hundreds" lever to print up to 9000 as well as to print the same amount by the "thousands" lever. The object of this is to effect a better setting up of the word printing in particular as well as the figure printing on amounts which do not include hundreds, for example five thousand and twenty which is better printed with the hundreds lever and the tens lever than with the thousands 60 lever and the tens lever because to use the thousands lever would leave a space for hundreds which is not required; also, when the amounts do not include tens the word 65 "and" can be printed.

In a general way if the machine is required to print pounds, shillings and pence the check or other forms are advantageously ruled and printed to take the words denoting the values in spaces allocated on the 70 forms for the purpose.

For the printing of values in dollars it may be preferable to operate the "hundreds" lever and its type sections for the latter to print from one hundred to nineteen 75 hundred and to use the "thousands" lever for two thousand and upwards to within the limit of the machine. The actual wording and figures to denote the values may be as desired and the same forms no part of my 80 invention.

The sections of the rollers are preferably mounted in substantially known manner on separate concentric sleeves each having its 85 separate toothed wheel by which the sleeve 90 and with it the section is rotated.

In operating the machine the levers are moved to positions opposite the values required and shown on scales and they may be held in these positions by any suitable 100 friction, spring or equivalent devices. When the machine is set the amounts can be easily 105 read by taking the scale figures opposite the levers; but for effecting a direct visible reading duplicate scales bearing the same 110

number values are attached to the pivoted levers, inside and adjacent to the front of machine casing so that when the machine is set to print, a corresponding amount on these 5 movable scales is visible through an opening in the machine casing sufficiently wide to permit one set of figures only to be seen.

Any suitable device may be employed 10 to return all the set levers to zero, such as 10 a bar adapted to move over the face of the machine and push the levers back.

The rotation of the sections for setting 15 is preferably continuous, that is to say to print one the section turns a certain distance, to print two it turns further, three further still and so on to the maximum value as differentiating from machines which turn in one direction for values to a certain amount and in the opposite direction for 20 values beyond that amount.

I will now describe my invention with 25 reference to the accompanying drawings in which:

Fig. 1 is a sectional view of the machine 25 and shows the same in the zero or ready for use position.

Fig. 2 is a top or plan view of the same 30 machine with part removed and the cover broken away. This drawing shows the type rollers in plain outline.

Fig. 3 is a front view of the case of the 35 machine and shows the scales thereon with the levers at various positions denoting a value which is seen on the reading off scale through apertures at the ends of the slots in which the levers are moved.

Fig. 4 is a sectional view of the numeral 40 rollers and shows how they are connected through sleeves to their respective toothed wheels and according to known practise.

In this example the machine which is 45 adapted to print values in British sterling comprises a base 1 and cover and frame 2. The base may be on india rubber feet but these are not shown.

The platen 3 is pivoted at 4 to a slide 5 mounted on the base and having limited movement at the slots 6. This slide is under the influence of spring 7 which cushions the 50 action of the hand lever.

The rollers 8 and 9 carrying the word 55 and figure type respectively, are mounted with their sleeves on spindles 10 and 11. This construction with relation to rollers 9 is clearly seen in Fig. 4 in which there are six such rollers each with a sleeve and its actuating toothed wheel.

The machine shown is adapted to print 60 amounts up to £9999-19-11 and is fitted with six levers, four for the pounds and one each for the shillings and pence. One of these levers 12 is seen in Fig. 1 and is pivoted at 13 to the frame of the machine. Rigid with the lever 12 is a toothed segment 65 14 in constant mesh with pinion 15 which

is mounted on the same sleeve as the toothed wheel 16. This wheel is in mesh with a toothed wheel on each of the spindles 10 and 11 so that when the lever is moved along its slot in the front of the machine 70 the segment rotates the toothed wheel 16 and causes it to simultaneously turn both the toothed wheels on spindles 10 and 11 and in so doing to also turn the corresponding type rollers the requisite amount to 75 bring both the word roller and the figure roller into correct printing position. When the lever is pulled to the requisite figure of the scale 17 on the front of the machine it is there held by spring plunger 18 engaging 80 a rack 19.

Inside the cover and attached to each 85 lever is a curved bar 20 bearing a scale on one side. This bar moves with the lever and exposes the figures of its scale at an 90 enlargement 21 made at the end of the lever slot. The figures on the outside and the inside scales correspond but are oppositely set with the result that when the lever is moved to a certain figure on the outside scale that 95 figure is shown through the opening 21. It will be seen in Fig. 3 that the levers are set to £2152-12-6 and that the same value is presented at the openings 21 where the amounts can be more easily read than they 100 would be at the different lever positions.

The platen 3 is connected by a link 22 to a pivoted side handle 23 by which the platen can be pulled to and pushed from the type 105 rollers but the latter movement is preferably effected by a coil spring, not shown, on the spindle 24.

The ribbon 25 is mounted on roller 26 and 110 sleeve 37 and passes behind a plate 28 having apertures 29, 29 opposite the type on 105 the rollers. This plate is mounted on brackets 30 which have slight sliding movement in slots 31. Light leaf springs 32 are placed between the plate and the frame of the machine.

A pivoted arm 33 is mounted at 34 on the 115 side of the platen and is provided with a pin 35 adapted to engage a notched wheel 36 on the spindle 27 so as to impart a small turning movement to the wheel and spindle 115 each time the platen is brought to the printing position. The said spindle 27 carries a free but close fitting sleeve 37 on which the ribbon is wound, the construction being such that if the ribbon is free to be wound 120 on the sleeve the latter will be turned when the notched wheel turns but if the ribbon is not free for further winding, the wheel and its spindle will turn but the sleeve held by the ribbon will remain stationary.

Much the same construction applies at 125 the roller 26 on which the ribbon is wound and unwound. This roller is rigid on spindle 39 and with ratchet wheel 40. A bell crank lever 41 is pivoted on spindle 39 130

and carries a spring 42 pressing against a pawl 43 which engages the ratchet wheel 40.

A slide bar 44 is pivoted to the lower end of the platen and moves in guides 45 on the frame 2. This slide bar has a stop 46 adapted to engage the nose 47 of a pivoted disc 48 and to turn the same when the platen is pulled to the printing position.

Rigid with the disc 48 is an arm 49 to which is connected a link 50 attached to a pivoted lever 51 said lever being in turn connected by another link 52 to a like lever 53. The lever 53 has a side arm 54 connected by a link 55 to the bell crank lever 40. 15 When the slide bar is thrust in it turns the disc 48 and effects a pull on the said links and consequent rocking of the levers 51, 53 and 41.

The levers 51 and 53 are in pairs each pair 20 carries an aligning bar 56 and 57 respectively. These bars are adapted to pass into spaces between the type on the rollers 8 and 9 and to thereby lock the rollers in correct alignment while the platen is pressing 25 against the type on them.

In practice the check or other paper to be printed is placed on the platen in usual manner, the levers are turned to the required positions and in turning they cause 30 their respective segments to rotate the toothed wheels and type rollers so that the type on them which corresponds with the setting of the levers is presented opposite the openings 29 in plate 28.

35 The platen is then pulled up to the type by means of handle 23 and the printing is effected.

Upon this movement of the platen the slide bar 44 strikes disc 48 and depresses 40 lever 49 thus drawing down the links 50, 52 and 55. Links 50 and 52 turn the levers 56 and 57 respectively and cause the bars thereon to lock the type rollers.

The link 55 inclines the lever 41 to the 45 right hand side and causes the pawl on it to impart a partial turn to the ratchet wheel 40 thus winding the ribbon on roller 26. When the ribbon is fully wound on this sleeve and the lever 41 is inclined to one side 50 the pawl is unable to further turn the ratchet wheel and rises up against the spring 42 and assumes a reversed position in relation to the ratchet wheel thereby permitting the ribbon to be drawn off the sleeve 38 by the 55 winding action at sleeve 37, the said sleeve 38 being turned in unwinding direction by the pawl 43.

For the purpose of returning the levers to zero I provide a U-shaped bar 58 pivoted 60 at 13 and adapted to simultaneously press back the levers to zero.

For repeatedly printing the same amounts the levers are left at the said amount and the platen may be moved to and fro as often 65 as is desired. Any locking or holding

means may be employed with the levers but in a general way the spring device 18 or its substitute is sufficient.

What I claim is:—

1. A machine for simultaneously printing 70 words and figures, including rotatable rollers divided into sections carrying the words and figures in type, toothed gears for operating the rollers, and pivoted levers having relatively rigid toothed segments for operating said toothed gears, the swinging of any one lever about its pivot simultaneously operating a word carrying and figure carrying section of the rollers, figure scales fixed to the machine frame adjacent each of the 75 levers, and a like scale fixed to and movable with each lever, said latter scales having their figure marks arranged reversely from that of the first mentioned scales.

2. A machine for simultaneously printing 80 words and figures comprising a frame, a platen pivotally mounted in relation to the frame, two sets of type-bearing rollers on parallel axes, toothed gear for simultaneously rotating the said rollers in pairs one 85 on each axis, pivoted levers for selectively rotating the toothed gear through the medium of toothed segments rigid with the levers, an inked ribbon between the platen and the rollers with means for bringing the platen against the inked ribbon and pressing it upon type on the rollers and means actuated by the movements of the platen to lock the type-bearing rollers with the type 90 in alignment previous to and while the 95 printing is being effected.

3. A machine for simultaneously printing 100 values in words and in figures comprising a frame, two rollers each comprising separately rotatable type-bearing sections mounted 105 on parallel axes on the frame, a sleeve fixed to each section, a toothed wheel fixed to each sleeve, a separate toothed segment engaging each toothed wheel each such segment being rigid with a pivoted lever, a pivoted platen mounted on the frame and adjacent the type-bearing sections, an inked ribbon between the platen and the sections, means for bringing the platen against the type 110 with the ribbon intervening and a movable guard between the ribbon and the platen with automatic means for progressively shifting the inking ribbon to cause it to travel from an unwinding sleeve to a winding 115 sleeve.

4. A machine for simultaneously printing 120 values in words and in figures, comprising a frame, two rollers, each comprising separately rotatable type-bearing sections mounted on parallel axes on the frame, a sleeve fixed to each section, a toothed pinion fixed to each sleeve, a toothed wheel fixed to each sleeve to engage and operate the type-bearing sections, a pivoted operating lever, and a toothed segment rigid with such 125 130

lever to engage and operate said toothed pinion, a pivoted platen mounted on the frame and adjacent the type-bearing sections, an inked ribbon between the platen and the sections, means for bringing the platen against the type with the ribbon intervening, and a movable guard between the

ribbon and the platen with automatic means for shifting the inking ribbon.

In witness whereof I have hereunto set my hand in presence of a witness.

JAMES HOWARD HORNER.

Witness:

HENRY FAIRBROTHER.
